Samuel E. Darby

UNITED STATES PATENT OFFICE.

ALONZO ALDRICH, OF BELOIT, WISCONSIN, ASSIGNOR TO BELOIT IRON WORKS, OF BELOIT, WISCONSIN, A CORPORATION OF WISCONSIN.

GUIDE FOR PAPER-MAKING MACHINES.

1,193,659.

Specification of Letters Patent.

Patented Aug. 8, 1916.

Application filed October 5, 1915. Serial No. 54,143.

To all whom it may concern:

Be it known that I, ALONZO ALDRICH, a citizen of the United States, residing at Beloit, in the county of Rock, State of Wisconsin, have made a certain new and useful Invention in Guides for Paper-Making Machines, of which the following is a specification.

This invention relates to guides for paper making machines.

The object of the invention is to provide guides for paper making machines which will insure proper feeding of the wet paper strips to the pressing rolls of the machine.

15 A further object of the invention is to allow adjustment in any direction of the guides.

A further object of the invention is to provide guides of the class described which will 20 eliminate the possibility of injury to the operator of the paper making machine in feeding the wet paper strips to the pressing rolls.

Further objects of the invention will appear more fully hereinafter.

The invention consists substantially in the construction, combination, location and relative arrangement of parts, all as will be more fully hereinafter set forth, as shown by 30 the accompanying drawing, and finally pointed out in the appended claims.

Referring to the drawing,—Figure 1 is a view in side elevation of the press rolls of a paper making machine, and embodying my 35 invention. Fig. 2 is a diagrammatic view showing the method of operation of the guide rolls.

The same part is designated by the same reference numeral wherever it occurs 40 throughout the several views.

In the paper making machine art, it is the present practice to provide press rolls to press water or liquid out of the strip of paper or paper pulp and also to smooth the 45 surface of the paper, and to provide a frame for the press or smoothing rolls and means to actuate one of the rolls, the other roll being actuated by friction contact therewith. In the present press or smoothing rolls, the 50 paper strips must be fed between the rolls by hand, making the operation dangerous and uncertain.

It is among the special purposes of my present invention to supply means to automatically feed the paper pulp between the

press or smoothing rolls thereby insuring proper feed and eliminating the element of danger to the operator.

In the drawing, and referring particularly to Fig. 1 thereon, 1 designates the usual frame of the press or smoothing rolls comprising vertical standards as shown, and having brackets 2 forming the bearing for the lower press roll 3 which may be driven to rotate in the direction of the arrow, by any suitable means, such as by a belt, not shown. The upper free ends of the vertical frames 1 are provided with pivot pins 4, on which are pivotally mounted arms 5 carrying at their free ends brackets 6 which form the bearings for the upper press roll 7. The press or smoothing roll 7 is rotated in the direction indicated by the arrow by frictional contact with the press roll 3. It is desirable to be able to adjust the roll 7 with respect to the roll 3, in order to relieve the pressure of the roll 7 upon the roll 3 and to prevent the flattening of the rolls' covering when at rest. I show a simple arrangement for the accomplishment of this result 80 wherein the frame is provided with a lug 8 directly beneath an extending portion 9 of the bracket 6 which is provided with an interiorly threaded hole therethrough. A rod 10 provided with screw threads as shown 85 and adapted to screw through the hole in the portion 9 rests upon the lug 8. It is obvious that by turning the rod 10 in one direction or the other, the roll 7 may be moved nearer to or farther away from the roll 3, about its pivot at 4. To facilitate the manipulation of the rod 10, I provide a handle 11 keyed thereto as shown.

In accordance with my invention I employ what I term two tape feed rolls and a 95 direction feed roll, each individually adjustable with respect to each other and with respect to the frame of the press or smoothing rolls, and all mounted on auxiliary frames adjustable with respect to the stationary 100 frame.

I show one simple arrangement embodying my invention wherein the frame 1 is provided with vertical slots therein as at 12 through which pass studs or bolts 13. An auxiliary frame 14, provided with horizontal slots 15 adapted to lie opposite the slots 12, is secured to the frame 1 by means of the bolts 13. By this arrangement, it will be seen that the auxiliary frame 14 may be 110

shifted vertically or horizontally with respect to the frame 1, by loosening the bolts 13, and may be rigidly secured to the frame 1 in any adjusted position by tightening said bolts. Similar bolts 16, 17 and 18, secure to the auxiliary frames 14, bearing plates 19, 20, and 21, respectively, each of said bearing plates being slotted as shown to allow adjustment in any direction with respect to the 5 auxiliary frames 14. The bearing plates 19 and 20 provide bearings for the tape rolls 22, 23, and the bearing plates 21, provide bearings for the direction feed roll 24. One of the tape rolls, such for instance, as tape 10 roll 22, may be caused to rotate in the direction of rotation of the press or smoothing roll 3, by means of sheaves located on each of said rolls, and a belt 25 connecting the sheaves. Wound around the tape rolls 22 15 and 23 are belts of tape, or other flexible belt material, as shown at 26.

It will be noticed that the direction feed roll 24 must be rotated in a direction opposite to the direction of rotation of the press 20 or smoothing roll 3. This may be accomplished in any desired way, such as by direct belting with a sheave on the roll 7 or by cross belting as indicated at 29, Fig. 2, with a sheave on the driving press or smoothing 25 roll 3. My invention, however, is not to be limited to these details.

From the foregoing it will be seen that the paper strips are thrown on the roll 7 as indicated at 28, in the usual manner. The 30 roll being rotated in the direction of the arrow by frictional contact with roll 3 causes the paper strips to be carried over the roll 7, over the auxiliary guide feed roll 24, where it comes in contact with the tapes 26 35 of the tape rolls 22, 23, thereby insuring proper feed of the paper strips between the press or smoothing rolls 7, 3, and thereby eliminating the necessity of the attendant reaching behind the rolls 7, 3, and to insure 40 the proper feed by hand.

As has been hereinbefore described, the roll 3 is journaled in fixed bearings and each of the rolls 7, 22, 23, and 24, or all of the rolls 22, 23, and 24, as a unit, may be moved 50 or adjusted relative to said roll 3 or to each other.

While I have shown and described one embodiment of my invention, it will be understood that many other arrangements embodying my invention will readily occur to those skilled in the art, and therefore my invention in its broad scope as defined in the claims is not to be limited or restricted to any detail or to the specific structure shown.

Having now set forth the objects and nature of my invention, what I declare as new and useful, and of my own invention, and desire to secure by Letters Patent, is,—

1. In a paper making machine, the combi-

nation with a press or smoothing roll frame, 65 of press or smoothing rolls journaled therein, auxiliary feed rolls also journaled in said frame and means operating between said auxiliary rolls for facilitating the feed of the paper between the press or smoothing 70 rolls.

2. In a paper making machine, the combination with a press or smoothing roll frame, of press or smoothing rolls journaled therein, tape feed rolls journaled in said 75 frame, feed tapes operating between said last mentioned rolls, and a direction feed roll located over and between said tape feed rolls to direct the paper from one of said press or smoothing rolls onto said tapes and 80 between said press or smoothing rolls.

3. In a paper making machine, the combination with a press or smoothing roll frame, of press or smoothing rolls journaled therein, and auxiliary feed rolls also journaled in said frame, and means to adjust independently each of said rolls in any direction relative to one of said press or smoothing 85 rolls.

4. In a paper making machine, the combination with a press or smoothing roll frame, of press or smoothing rolls journaled therein, tape feed rolls journaled in said frame, feed tapes operating between said last mentioned rolls, and a direction feed 90 roll located over and between said tape feed rolls to direct the paper from one of said press rolls onto said tapes and between said press or smoothing rolls, means to vertically 95 adjust one of said press or smoothing rolls relative to the other and means to adjust each of said tape rolls and said direction feed roll relative to said press or smoothing rolls and to each other.

5. In a paper making machine, the combination with a press or smoothing roll frame, of press or smoothing rolls journaled therein, tape feed rolls journaled in said frame, feed tapes operating between said last mentioned rolls, and a direction feed 105 roll located over and between said tape feed rolls to direct the paper from one of said press or smoothing rolls onto said tapes and between said press or smoothing rolls, means to vertically 110 adjust one of said press or smoothing rolls relative to the other and means to adjust said direction feed roll and said tape rolls as a unit relative to said press or smoothing rolls.

6. In a paper making machine, the combination with a press or smoothing roll frame, of press or smoothing rolls journaled therein, means to adjust one of said press or smoothing rolls relative to the other, auxiliary frames adjustably secured to said 120 press or smoothing roll frame, tape rolls carried by said auxiliary frame, means to rotate one of said tape rolls, tapes operating 125

over said tape rolls, a direction feed roll carried by said frame, and means to rotate said direction feed roll.

7. In a paper making machine, the combination with a press or smoothing roll frame, of press or smoothing rolls journaled therein, auxiliary frames adjustably secured to said press or smoothing roll frame, bearing plates adjustably secured to said auxiliary frame, a roll carried by each of said bearing plates, means to drive two of said rolls from a common source, and means to drive a third roll from one or the other of said rolls.

15 8. In a paper making machine, the com-

bination with a press or smoothing roll frame, of press or smoothing rolls journaled therein, auxiliary rolls mounted on said frame, and a tape operating over said auxiliary rolls to facilitate the feeding of the 20 paper between said press or smoothing rolls.

In testimony whereof I have hereunto set my hand in the presence of the subscribing witnesses, on this 1st day of October, A. D. 1915.

ALONZO ALDRICH.
